CLAIM

The ornamental design for a jewelry cleaner, as shown and described.

DESCRIPTION

FIG. 1 is a perspective view of a jewelry cleaner according to our new design;

FIG. 2 is a rear view of the jewelry cleaner of FIG. 1;

FIG. 3 is a front elevation view of the jewelry cleaner of FIG. 1;

FIG. 4 is a right side elevation view of the jewelry cleaner of FIG. 1, the left side elevation view being a mirror image thereof; and,

FIG. 5 is a top view of the jewelry cleaner of FIG. 1.

The bottom view forms no part of the claimed design.

The broken lines shown in the drawings are for the purpose of illustrating unclaimed portions of the jewelry cleaner, and form no part of the claimed design.
